UNITED STATES PATENT OFFICE.

JAMES A. STIRLING, OF ELKHART, INDIANA, ASSIGNOR, BY MESNE ASSIGNMENTS, TO CHICAGO TELEPHONE SUPPLY COMPANY, OF ELKHART, INDIANA, A CORPORATION OF DELAWARE.

WATCHCASE RECEIVER.

Application filed December 1, 1924. Serial No. 753,323.

My invention relates to telephony and more particularly to a telephone receiver of the watch case type.

Receivers of this general type are now commonly employed in the head set or head phones for radio reception.

It is desirable to make the head phone as light as is consistent with good reception for the convenience of the wearer. It is 10 also highly desirable to have the receiver as sensitive as possible and to secure, as nearly as possible, uniformity in the output in order that the two receivers of a given head set may be matched in tone and receiving 15 characteristics.

It is furthermore highly desirable to design the parts of a device of this character so that assembly may be accomplished in a simple and inexpensive manner with the 20 assurance that the resulting structure will be properly and permanently assembled and that the successive units of assembly will be uniform in character.

According to my invention, I provide a 25 metal aluminum shell or case which has its outer periphery threaded and the edge of the metal forms a seat for a tone plate which, in turn, has a relatively wide peripheral seat for the diaphragm. This tone 30 plate improves very decidedly the quality of reception of the receiver, being spaced close to the diaphragm and operating like a sounding board on the sound waves generated by the moving diaphragm. The magnetic system is mounted on this tone plate 35 and is otherwise free of contact with the casing so that any vibrations in the magnetic system itself may be added to that of the tone plate to secure a co-operation between the tone plate and the diaphragm in 40 re-enforcing sound vibrations.

In addition to the above improvement, I 45 provide an improved form of pole piece which performs, in addition to its mechanical function which is an improvement, an important function in the magnetic system, that is, to form an auxiliary gap which assists first, in securing a uniformity of stress upon the diaphragm, and uniformity 50 of tone in sound production.

I provide other incidental mechanical improvements which will be apparent from the following detailed specification.

In the accompanying drawings I have

illustrated an embodiment of my invention 55 which will teach those skilled in the art how to construct and operate a device in accordance with my invention.

In the drawings:

Figure 1 is a plan view of a device showing the diaphragm removed and the gear speed in section. This figure is taken on the line 1—1 of Fig. 3;

Fig. 2 is a section taken on the line 2—2 of Fig. 3, showing the magnet system in 65 bottom plan view;

Fig. 3 is a transverse section taken on the line 3—3 of Fig. 1;

Fig. 4 is a transverse section taken at right angles thereto and on the line 4—4 70 indicated in Fig. 1;

Fig. 5 is an isometric view of one of the pole pieces;

Fig. 6 is a side elevational view of the tone plate and magnet; 75

Fig. 7 is a back view of the terminal block and mounting plate showing the lugs struck up from the plate for engaging the terminal block;

Fig. 8 is a fragmentary section through 80 one of the inserts in the terminal block; and

Fig. 9 is a diagrammatic illustration of an embodiment of the illustration.

The receiver which I have selected to illustrate my invention comprises a shell 10 85 which is drawn sheet aluminum of approximately 14 gauge. This shell has a back or bottom plate 11 with a cylindrical rim flared out as indicated at 12 to a larger diameter providing the threaded portion 13. The inside of the threaded portion is carefully finished to the desired diameter and the threaded portion 13 is adapted to receive the threads of the cap 14, which cap is screwed down to hold the diaphragm 15 and the 90 tone plate 16 with its connected parts in position. The tone plate 16, which also may be termed an assembly plate, has a raised rim 17 which is stamped up about a 32nd of an inch above the central portion of the 100 plate. This plate 16 also has a central aperture 18 through which project the free ends or upright ends of the pole pieces 19. The plate 16 has three screw holes 20, 21 and 22 105 therethrough, which are threaded to receive clamping screws 23, 24 and 25, respectively, for holding the magnet system and the terminal block, respectively, upon the assembly

105

plate 16. The plate 16 which is made of sheet aluminum has its edge about the aperture 18 re-enforced as indicated at 26 by stamping the same and slightly offsetting in order to re-enforce the same against bending. This re-enforcing does not extend completely around the periphery but only part way. The plate 16 also has a pair of integral lugs 27, 27 struck down to engage the ends of the 10 terminal block 28 to hold the same against rotation. The terminal block 28 is made up of a pair of stampings of fibre, or the like, with the screws 25 passed through the center of the same and holding the block upon the 15 plate 16. The terminals themselves are formed of sheet metal washers 29 having the integral ears 30 to which are connected the ends of the windings of the coils. These terminal washers 29 are held in place upon 20 the block 28 by means of an insert 31 which is formed of a threaded brass thimble, the outside of which is knurled. This thimble is pushed into registering openings in the two parts of the terminal block 28 to hold 25 the same together. The sleeve 31 has a head which engages the washer 29 and holds the same firmly in electrical and mechanical contact. Suitable screws 32 are threaded into the sleeves 31 and the terminals of the 30 flexible cord 33 are fastened under said screws 32. The casing or shell 10 has an aperture at 34 for the flexible cord shown at 33.

It will now be seen that by means of the 35 single screw 25 threaded into the hole 22 in the plate 16, and the struck up lugs 27, the terminal block 28 is held firmly in position upon the plate 16.

The magnet system which is assembled 40 upon the plate 16, comprises the permanent horse-shoe magnet 35 formed preferably of rectangular cross section with the sides thereof ground parallel. This magnet is bent into circular form and the ends thereof 45 have openings through which the screws 23 and 24 pass to mount the magnet system upon the assembly or tone plate 16.

The pole pieces of the magnets 35 are separated from the assembly plate 16 by means 50 of the collars or posts 36 which serve to bring the ends or upright parts of the pole pieces 9 the proper distance from the diaphragm 15. As heretofore explained, the magnets 35 are carefully ground to size.

The pole pieces 19 comprise the base portion 38 and the upright end portions 39. The base portion 38 is provided with a hole 40 through which passes one of the screws 23, 24 to clamp the pole piece to its appropriate magnet pole. At the junction of the base with the upright, I have struck out a lug 41 which lug cooperates with the corresponding lug on the cooperating pole piece. That is to say, the pole pieces 19 are 65 made in left and right pattern with the lugs

41 extending towards each other each in the plane of its own base. Thus an auxiliary magnetic gap 42 is formed which has an important function in the device. At the same time, this lug 41 forms in each case a 70 suitable support for the head or press board washer of the electrical windings 44 for each pole piece 19. At their upper ends the windings 44 are held by suitable washers or heads 45, these heads preferably consisting 75 of a brass cover and a fibre washer, the edges of the upright portion being riveted over slightly to hold the windings in place. In the assembly of the parts, the windings are assembled upon the pole pieces and then the 80 pole pieces, the magnets and the posts are assembled upon the mounting plate 16. Now, it will be observed that in drawing the screws 23 and 24 tight, there may be a tendency 85 to buckle the mounting plate 16, particularly in the vertical line 4-4 shown in Fig. 1, and it is to prevent this that the re-enforcing or stamping at 26 has been resorted to. There is not as much tendency to 90 distort the lower part of the plate 16 since the terminal block 28 offers resistance to bending in one direction. I find that the stamping and offsetting of the portion 26 considerably strengthens this plate without 95 interfering with its function as a tone plate.

After the parts have been assembled in place and the washers 29 and 30 connected to the windings 44, the air gap between the upright ends of the pole pieces 19 and the diaphragm 15 is carefully ground to a predetermined size, the raised rim of the tone plate upon which the diaphragm seats, being also ground off in a parallel plane so as to afford a good seat for said diaphragm 15.

It will be seen from the above that I have provided a structure which is easily and inexpensively manufactured and assembled and which is capable of manufacture with the assurance of uniformity of the product. The windings 44 are preferably made of enameled Advance wire so that the resistance thereof does not change appreciably with temperature.

The employment of the auxiliary magnetic gap 42, which is illustrated diagrammatically in Fig. 9, gives the receiver unique characteristics. Due to the auxiliary gap 42, there is not the tendency for the magnet 35 to weaken if permitted to remain without a proper keeper. Also due to this auxiliary gap, the upper ends of the pole pieces are much freer magnetically to have the flux therethrough changed by the windings 44, than would be the case where such auxiliary gap were not provided. That is to say, assume that the flux of the permanent magnet 35 is a constant, a certain portion of the same will pass through the main air gap 120 through the diaphragm 15 and back to the 125

co-operating pole piece, and another part of the magnetism will tend to pass through the air gap 42.

Obviously if the flux through the upper ends of the pole pieces above the gap 42 is to be varied, some means should be provided for permitting such variation to occur with a minimum of effort. That is to say, if no auxiliary gap were provided then 10 the magnet lines of force could be choked out of the pole pieces only by main strength of the current going through the windings 44. In the structure of my invention it is not necessary for the flux to be changed in 15 the permanent magnet 35, the path which the flux takes being merely shifted. Hence, upon a very slight opposition to the flow of magnetism up through the main air gap, such magnetism may be diverted to the 20 auxiliary gap 42. Thus a very sensitive receiver is provided and the condition of sensitivity is inherent in the structure. The auxiliary gap 42 is greater than the sum of the two main air gaps. Also, there is less 25 danger of the permanent magnet 35 weakening through the course of time, because of the auxiliary gap 42.

I do not intend to be limited to the details shown or described.

30 I claim:

1. In a telephone receiver, a shell of sheet metal drawn into a cup, said cup having the rim thereof flared out, said rim having its periphery threaded, the edge of the cup forming a narrow seat, a tone plate formed of relatively thick sheet aluminum having a plane peripheral edge forming a relatively wide seat for a diaphragm, a diaphragm on said seat, a cap threaded on said cup and 35 clamping the edge of the tone plate and the diaphragm, said tone plate having its central portion depressed slightly below the diaphragm seat, and a magnet system mounted upon the tone plate and projecting 40 through the same into proximity to the diaphragm.

2. In combination, a cup, a cap threaded to the edge of the same, a sheet metal tone plate comprising a planar rim providing a wide seat, a diaphragm on said seat, the body of the tone plate being depressed a short distance below the rim, said body having an opening through the center, a magnet system clamped to the plate and 50 projecting through said opening, a terminal block mounted on said plate, a screw passing through said terminal block and threaded into said tone plate, said tone plate having integral lugs struck down into contact 55 with the block to hold the same against turning.

3. A tone plate comprising a sheet of aluminum having a raised flat edge forming a diaphragm seat, said plate having a 60 central aperture for the magnet system, the

edge of the aperture being compressed by stamping to harden the same.

4. A tone plate comprising a sheet of aluminum having a raised flat edge forming a diaphragm seat, said plate having a central aperture for the magnet system, the edge of the aperture being reinforced, and integral lugs struck down from the edge of the aperture for engaging a terminal block.

5. A magnet pole piece for a watch case receiver comprising a sheet metal stamping consisting of a base portion adapted to engage the pole of a permanent magnet and an end portion lying in a plane at substantially right angles to the plane of the base portion, said end portion having an integral lug struck therefrom and extended in the plane of the base portion and forming a seat for the magnet winding. 80

6. A magnetic pole piece for a watch case receiver comprising a sheet metal stamping consisting of a base portion adapted to engage the pole of a permanent magnet and an upright portion lying in a plane at substantially right angles to the plane of the base portion, said upright portion having an integral lug struck from the center thereof and extending in the plane of the base portion and forming a seat for the end of the winding for said pole piece. 85

7. In combination, a tone plate having a raised rim forming a diaphragm seat, a central opening, a magnet system comprising a horse-shoe magnet, posts between the ends of the magnet and the plate, pole pieces projecting from the ends of the magnet through said opening, a screw for each pole piece passing through the adjacent end of the magnet, through the post and threaded into the plate. 90

8. In combination, a tone plate having a raised rim forming a diaphragm seat, a central opening, a magnet system comprising a horse-shoe magnet, posts between the ends of the magnet and the plate, pole pieces projecting from the ends of the magnet through said opening, a screw for each pole piece passing through the adjacent end of the magnet, through the post and threaded into the plate, and windings for said pole pieces, said windings having washers adapted to lie in said opening in the plate for spacing said pole pieces. 105

9. In combination, a tone plate having a raised rim forming a diaphragm seat, a central opening, a magnet system comprising a horse-shoe magnet, posts between the ends of the magnet and the plate, pole pieces projecting from the ends of the magnet through said opening, a screw for each pole piece passing through the adjacent end of the magnet, through the post and threaded into the plate, said pole pieces comprising base portions which are clamped flat against the ends of the magnet and upright por- 110 115 120 125 130

- 4
- tions disposed centrally of the tone plate, said pole pieces having lugs struck out of the upright portions and extending towards each other, windings having heads supported by said lugs, said lugs projecting towards each other and forming an air gap between them of greater extent than the air gap of said pole pieces with their co-operating diaphragm.
- 10 10. In combination, a permanent magnet having pole pieces, said pole pieces having base portions and upright portions, lugs struck out of the upright portions extending in the plane of the base, windings for the upright portions, said windings comprising heads supported upon said base portions and upon said lugs.
11. In combination, a permanent magnet having pole pieces, said pole pieces having base portions and upright portions, lugs struck out of the upright portions extending in the plane of the base, windings for the upright portions, said windings comprising heads supported upon said base portions and upon said lugs.
- 20 15. In combination, a permanent magnet having pole pieces, said pole pieces having base portions and upright portions, lugs struck out of the upright portions extending in the plane of the base, windings for the upright portions, said windings comprising heads supported upon said base portions and upon said lugs, said lugs extending towards each other and forming an auxiliary gap of greater spacing than the diaphragm gap and substantially less than the spacing of the pole pieces.
- 25 30. 12. In combination, a tone plate comprising a sheet of relatively soft non-magnetic material having a raised rim forming a diaphragm seat, said plate having a central
- aperture, a terminal block adjacent the aperture, a pair of terminals at the ends of said block, a central screw passing through the block and into the plate, said plate having lugs struck up from the edges of the aperture to engage the ends of the block.
13. In combination, a permanent magnet, a tone plate having a central aperture, supporting posts between the poles of the magnet and the tone plate, screws passing through the poles and through the posts and secured to the tone plate, the edge of the tone plate about said aperture being stiffened to prevent distortion by attachment of said magnet.
14. In combination, a permanent magnet, a tone plate having a central aperture, supporting posts between the poles of the magnet and the tone plate, screws passing through the poles and through the posts and secured to the tone plate, a terminal block having a central screw passing through said tone plate between said screws, which supports the magnet.
15. In combination, a permanent magnet, soft iron pole pieces comprising flat bases and parallel upright portions, and an auxiliary air gap formed by striking out lugs from the parallel up-right portions.

In witness whereof, I hereunto subscribe my name this 26th day of November, 1924.

JAMES A. STIRLING.
